UNITED STATES PATENT OFFICE.

EARL S. SWARTZBAUGH, OF WEST HELENA, ARKANSAS.

BRAKE FOR RAILWAY ROLLING STOCK.

Application filed September 15, 1923. Serial No. 662,810.

To all whom it may concern:

Be it known that I, EARL S. SWARTZBAUGH, a citizen of the United States, residing at West Helena, in the county of 5 Phillips and State of Arkansas, have invented certain new and useful Improvements in Brakes for Railway Rolling Stock, of which the following is a specification.

This invention relates to certain new and 10 useful improvements in brakes for railway rolling stock, and has particular reference to devices of that kind, wherein means is provided upon the rolling stock for gripping engagement with the rails forming the 15 track upon which the stock runs, whereby the rolling stock is effectively maintained or retained in a stationary position.

The primary object of the invention is 20 to provide a device of the above kind primarily adapted to be operated after the rolling stock has been brought to a stop for preventing accidental movement thereof, as distinguished from brakes adapted to bring the rolling stock to a stop.

25 Another object of the invention is to provide a brake of the above character which embraces the desired qualities of simplicity, and durability of construction, as well as efficiency in operation.

30 A further object is to provide a brake for railway vehicles embodying clamps carried at each side of the vehicle and manually operable means for simultaneously operating said clamps for engaging the same with the rails or disengaging the same therefrom, the clamps each embodying a 35 pair of cross pivotally connected clamping jaws mounted to swing in a direction transversely to the line of travel of the railway vehicle.

40 With the above general objects in view and others that will become apparent as the nature of the invention is better understood, the same consists in the novel form, combination and arrangement of parts, hereinafter more fully described, shown in the accompanying drawings, and claimed.

45 In the drawings, wherein like reference characters indicate corresponding parts throughout the several views:

Figure 1 is a top plan view of a truck forming part of a railway vehicle or rolling stock and equipped with a brake constructed in accordance with the present invention.

50 Figure 2 is a transverse sectional view

taken substantially upon the line 2—2 of Figure 1,

Figure 3 is an enlarged fragmentary view in longitudinal section substantially upon the line 3—3 of Figure 2, and 60

Figure 4 is a fragmentary sectional view, taken on the line 4—4 of Figure 1.

Referring more in detail to the drawings, the wheeled truck of the rolling stock embodies a pair of longitudinal side frame bars 65 5 arranged in parallel spaced relation at each side of the truck and rigidly connected by means of end cross bars 6, the rail engaging wheels 7 of the truck being suitably mounted between the pairs of bars 5 to run 70 upon the tracks or rails 8, in a well known manner.

The cross bars 6 of the truck frame are respectively arranged adjacent the front and rear ends of the truck and connecting the 75 inner ones of the pairs of side bars 5 midway between their ends is a further cross bar 9 that is braced at its ends as at 10, said bar 9 being disposed upon the upper flanges of the inner bars 5 and the braces 80 10 being secured at their outer ends to the lower flanges thereof, as shown clearly in Figure 2.

The side frame bars 5 of each pair are rigidly connected intermediate their ends by 85 means of transverse brackets 11 that are arranged in adjacent spaced relation and which are preferably of channel form in section with their flanges directed away from each other and secured to the webs of 90 the side frame bars 5. A clamp is disposed between each pair of brackets 11 and each clamp embodies a pair of vertical swinging jaws 12 which cross each other and which are mounted upon a pivot pin 13 that passes 95 through the pairs of brackets 11 and thru the jaws 12 at their point of crossing. The lower ends of the jaws 12 thus depend at opposite sides of the ball of the rails 8 as shown in Figure 2, so that they may be 100 swung toward each other for tightly gripping the ball of the rail in a manner which will presently become apparent.

By means of the above construction, a pair of clamps is provided, one arranged at 105 each side of the truck, and both arranged in transverse alignment, the upper ends of the inner jaws being disposed outermost, and the upper ends of the outer jaws being innermost as shown in Figure 2. A horizontally 110

swinging hand lever 14 is loosely pivoted and slidably connected as at 15 to the central portion of the transverse bar 9, preferably by pin and slot connection, as shown, and the short end of this lever is attached, as at 16, to the inner end of a pair of links 17 and 18 that are respectively connected as at 19 and 20 to the upper end of the outer jaw of the clamp at one side of the truck and to the upper end of the inner jaw at the other side of the truck. At the opposite side of the pivot 15, the lever 14 has a pair of links 21 and 22 pivoted thereto as at 23 at their inner ends, the outer ends of said links 21 and 22 being respectively pivoted to the other jaws of said clamps. In the construction shown, the link 21 is connected to the upper end of the inner jaw at one side of the truck and the link 22 is connected to the upper end 20 of the outer jaw at the other side of the truck.

It will thus be seen that when the lever 14 is swung to the left of Figure 1, as shown, the several jaws are swung toward each other so as to tightly grip opposite sides of the ball portions of both of the rails 8, whereby the rolling stock is effectively restrained against movement upon the rail as long as the lever 14 is held in this position. On the other hand, when the lever 14 is swung to the right of Figure 1, the jaws of the two clamps are caused to separate so as to disengage from the rail and allow free movement of the rolling stock thereon. For holding the lever 14 in either position, with the clamps released or engaged, any suitable

means may be provided such as a downwardly directed tooth or pawl 24 formed rigidly or otherwise suitably carried by the lever 14, in position to engage the teeth 25 formed upon the upper edge of the transverse frame bar 6 at that end of the truck toward which the lever 14 projects. As the handle 14 is relatively long and projects at one end of the railway vehicle, it may be conveniently grasped for being swung to operate the clamp.

In view of the foregoing description, it will be seen that I have provided a very simple and durable form of brake for railway vehicles which may be cheaply and easily manufactured and installed upon existing rolling stock, and which may be conveniently operated for effectively serving the purposes above mentioned.

Minor changes may be made without departing from the spirit and scope of the invention as claimed.

What I claim as new is:

In combination with a wheeled truck of a railway vehicle, a cross bar mounted thereon and provided at a point midway between its ends with a longitudinally disposed slot, a lever having a fulcrum pin which is loosely received in said slot, clamping jaws pivotally mounted upon the truck at the opposite ends of the cross bar and links pivotally connected at their inner ends with the lever and pivotally connected at their outer ends with the clamping jaw.

In testimony whereof I affix my signature.

EARL S. SWARTZBAUGH.
